APERTURED ELECTRODE FOR THERMIONIC TUBES

Harry S. Bamford, Philadelphia, Pa., assignor, by
mesne assignments, to Farnsworth Television &
Radio Corporation, Dover, Del., a corporation
of Delaware

Application October 31, 1936, Serial No. 108,553

3 Claims. (Cl. 250—27.5)

My invention relates to apertured electrodes for use in thermionic tubes, and more particularly to an electrode in the form of a knitted fabric. This application is a continuation in part of the prior applications of Farnsworth and Bamford, Serial Numbers 20,158 and 20,159, both filed May 7, 1935. Application Serial No. 20,158 has since matured into U. S. Patent No. 2,066,070, issued December 29, 1936. Application Serial No. 20,159 is now U. S. Patent No. 2,155,478, issued April 25, 1939.

In the patents above referred to, there was described and claimed a knitted fabric of refractory wires which was positioned in an oscillograph tube to be raised to incandescence by the impact of a moving cathode ray beam, thereby producing a visual image. The mesh of the fabric was preferably less than the number of elemental areas desired in the image.

The advantages gained by the use of an inherently elastic screen, such as one produced by knitting, were set forth therein, the inventions being particularly valuable to maintain the screen substantially flat under the differential and extreme heating thereof by electron impact.

I have found that a conductive knitted screen is also valuable for use as an electrode in a thermionic tube, where the screen is differentially heated even though the maximum heating encountered is less than that sufficient to raise it to incandescence, and I have also found that a knitted fabric of relatively open mesh is ideally adapted for use as an accelerating electrode where electrons pass therethrough, as well as for use as a photoelectric electrode when electrons are to be emitted from one side of the fabric and drawn through the meshes to be utilized on the opposite side. I have further found that, when the fabric is not heated to incandescence, it is not necessary to make the fabric from highly refractory material.

It is therefore the main object of my invention to provide an electrode in a thermionic tube which will maintain a desired contour under differential heating.

Another object of my invention is to provide an accelerating electrode which will not warp or break under differential heating.

A further object of my invention is to provide a base for a photoelectric emitter which will not depart substantially from a predetermined position under the heat of illumination.

A still further object is to form a strong mesh screen from exceptionally fine wires.

Other objects of my invention will be apparent

or will be specifically pointed out in the description forming a part of this specification, but I do not limit myself to the embodiment of the invention herein described, as various forms may be adopted within the scope of the claims.

In referring herein to a warp knit fabric, the term shall be deemed to include all weaves where a single wire is formed with a series of loops through which another row of loops is passed and so on consecutively until the required area is produced. This type of weave has the advantage that, when the selvage edges thereof are fixed to a support, no direct pull can be exercised against the support along a single wire or thread. It is, of course, known in the art that, if mesh screens are utilized, it is possible to prevent breakage to a large extent by welding each particular cross-over of the individual wire components. Such a welding, however, is impractical and well-nigh impossible when dealing with exceedingly fine wires, and inasmuch as my invention herein described contemplates the use of wires as fine as 0.0005 inch, it is obvious that welding of each individual cross-over would be difficult without breaking or weakening the wires to an extent preventing practical use.

My present invention allows a screen of exceedingly fine wire to be used where the ratio of mesh aperture to wire material can be as low as 5 to 1 or as high as 100 to 1, depending upon the use to which the electrode is to be put.

In order to more fully illustrate my invention, I have shown in the drawing two preferred uses of my knitted fabric electrode.

Figure 1 is a diagrammatic view and circuit showing a knitted fabric utilized as an electrode in an oscilloscope.

Figure 2 is a diagrammatic view of a photoelectric tube wherein one side of a mesh electrode is illuminated and electrons drawn through the apertures in the mesh, to be utilized on the opposite side of the electrode.

Figure 3 is a plane view of the fabric screen and support, not to scale.

Explaining more in detail, and referring directly to Figure 1, an envelope 1 is provided at one end with a reentrant stem 2 carrying a cathode 3 capable of emitting electrons. An anode 4 is provided with an aperture 5 presented to the cathode in order that electrons emitted from the cathode may be accelerated through the aperture and toward the opposite end of the envelope, on the end wall 6 of which is deposited a fluorescent screen 7. A control grid 8 is preferably positioned between the cathode 3 and

the anode aperture 5, by means of which signals from an input lead 9 may be utilized to control the intensity of the beam passing through the anode aperture.

5 The cathode is energized by cathode heating battery 10 and an accelerating potential is placed upon anode 4 by anode source 11. In case additional acceleration is desired an auxiliary accelerating electrode may be used, and I prefer to 10 position this electrode between anode 4 and the fluorescent screen 7. This accelerating electrode embodies my present invention and comprises an electrode support ring 12, across which is stretched a knitted fabric 14. The fabric is 15 maintained in position, preferably by splitting support 12, placing the fabric across one half of the ring, placing the other half over the fabric, and welding both halves to fix the fabric between the two half rings. The fabric 14 is knitted, and 20 I have found that the fabric may be knitted on standard knitting machines, such as, for example, those utilized to make silk stockings, and the wire utilized for the accelerating fabric may be, for example, molybdenum, tantalum, tungsten, 25 nickel, or any ductile metal of lower melting points, in case the accelerating electrode is not subjected to heavy bombardments.

Inasmuch as the accelerating electrode here is used only for the production of an accelerating field, it is obvious that within certain limits 30 the mesh aperture should be large in proportion to the wire diameter; in other words, here it is desired that the large majority of the electrons shall pass through the electrode, and as few as 35 possible intercepted thereby. This is, of course, in sharp contrast to the two above-mentioned patents, where it was desired to intercept as many electrons as possible in order to produce bombardment of the fabric. I therefore utilize 40 very fine wire for the fabric and make the meshes relatively large, and I have found that it is possible to make a satisfactory accelerating electrode fabric where the ratio of wire diameter to mesh aperture diameter is 100 to 1.

45 After the accelerating electrode has been mounted in the desired position, an exterior lead 15 is provided so that the electrode may be given an accelerating potential from auxiliary source 16. The tube is then exhausted, and when 50 placed in operation the beam from anode 4 may be deflected over the screen in a pattern as predetermined by the action on the beam of scanning oscillators 17 and 18, energizing magnetic deflection coils 19 and 20, respectively.

55 It will thus be seen that the accelerating electrode 14 is subject to differential heating which, if not compensated for, will tend to buckle or displace the fabric out of its normal plane, thereby changing the electrostatic field set up 60 by it and distorting the image produced on the screen 7. The loops of the knitted fabric, however, quickly absorb the expansion and contraction of the wires due to the passage thereover of the beam, and prevent any substantial distortion from the normal plane of the fabric as 65 a whole. I have thus been able to utilize, without welding at cross-overs, a fabric screen electrode having exceptionally fine wire sizes, without breaking and without any substantial deviation from the normal plane.

70 In the example given above, the differential heating of the screen occurs by reason of the passage thereover of a moving electron beam. In the example shown in Figure 2, however, the

differential heating is caused by an entirely different factor. Here I have shown, in its very simplest form, a photoelectric tube comprising a cathode and an anode 21. The cathode in this case comprises a support 12, exactly similar to that previously described, and a knitted fabric 14 supported thereby in exactly the same manner as previously described, except that in this case I prefer to form the wires of the fabric from silver and to make the wire-to-aperture-size ratio between 1 to 5 and 1 to 100, depending upon circumstances, and I have found that there is no difficulty in knitting fine silver wire to the smaller mesh. The silver cathode, in this case, is supported on a stem 22, the anode 21 is supported 10 from the wall by lead 23, and the difference of potential is placed between the cathode and anode by source 24 operating through output device 25, which may well be a work circuit. After the silver fabric has been mounted in position it 15 may then be oxidized and sensitized from a source of caesium or other material 26 having a low work function, as is well known in the art.

If, then, an image from light source 27 is thrown on the silver screen 14 through a lens 28, 25 different parts of the silver screen will be illuminated to a greater or lesser degree and, in consequence, heated to a greater or lesser degree; and if the knitted fabric is utilized here the entire cathode will maintain its normal plane in spite 30 of its differential heating, and thus the field between the anode and cathode will not become distorted. Electrons emitted on the front surface of the fabric 14 will be pulled through the apertures by the accelerating potential and over to 35 anode 21, and if it is desired, a focusing coil or other focusing device may be utilized between anode and cathode to maintain the electrons in parallel relationship so that an electron image may be formed which can be utilized in any desired manner, although my cathode screen in 40 this case is not by any means limited to use in forming such an electron image.

I have therefore provided and given two instances of electrodes within a thermionic tube 45 envelope which are subjected to differential heating, and which will, if made of knitted fabric, maintain their normal planes under such differential heating without the necessity of welding cross-overs, thus allowing an extremely fine wire 50 to be utilized in making the fabric. I have thus been able to greatly reduce the area of the electrode as far as wire size is concerned, and have provided an exceptionally strong screen and one 55 which cannot be warped or distorted in use, thereby preventing field distortions when energized.

I claim:

1. An electrical discharge tube having an envelope containing an electrode comprising a fabric of refractory wire, said fabric having a single wire formed into a single chain of loops through which another row of loops of said wire is passed to produce a warp knit fabric, and a cooperating electrode. 60

2. An electron discharge tube having an envelope containing an electrode comprising a warp knit fabric of refractory wire stretchable in all directions, and a cooperating electrode. 65

3. Apparatus as recited in claim 1, wherein the 70 fabric of refractory wire is provided with a coating of photoelectric material.
